(57) **CLAIM**

The ornamental design for a plastic bag carrying handle, as shown and described.

DESCRIPTION

FIG. 1 is a front perspective view of the plastic bag carrying handle with a bag shown in dotted lines for illustrative purposes only and forming no part of the claimed design; FIG. 2 is a front elevational view thereof; FIG. 3 is a rear side elevational view thereof; FIG. 4 is a left side elevational view thereof with the right side elevational view being a mirror image thereof; FIG. 5 is a top plan view thereof; FIG. 6 is a bottom plan view thereof; FIG. 7 is a front elevational view of the plastic bag carrying handle in a folded orientation; FIG. 8 is a rear side elevational view of the plastic bag carrying handle in a folded orientation; FIG. 9 is a left side elevational view of the plastic bag carrying handle in a folded orientation with the right side elevational view being a mirror image thereof; FIG. 10 is a top plan view of the plastic bag carrying handle in a folded orientation; and, FIG. 11 is a bottom plan view of the plastic bag carrying handle in a folded orientation.
The surface texture that is shown on portions of some of the surfaces of the handle is understood to exist on the entire surface on which it is shown.
